UNITED STATES PATENT OFFICE.

ERWIN R. STOEKLE, OF MILWAUKEE, WISCONSIN, ASSIGNOR TO THE CUTLER-HAMMER MFG. CO., OF MILWAUKEE, WISCONSIN, A CORPORATION OF WISCONSIN.

THERMALLY-CONTROLLED CIRCUIT INTERRUPTER.

Application filed May 9, 1921. Serial No. 468,158.

To all whom it may concern:

Be it known that I, ERWIN R. STOEKLE, a citizen of the United States, residing at Milwaukee, in the county of Milwaukee and State of Wisconsin, have invented new and useful Improvements in Thermally- Controlled Circuit Interrupters, of which the following is a full, clear, concise, and exact description, reference being had to the accompanying drawing, forming a part of this specification.

This invention relates to thermally controlled circuit interrupters and more particularly to those of the fluid contact type. In the construction of such controllers, great difficulty has heretofore been experienced in providing for positive automatic resetting thereof, due chiefly to the fact that the fluid contacting medium tends very strongly upon reflux thereof to entrap one or more bubbles of air or the like which prevent such reestablishment of electrical continuity. Moreover, such difficulty is not materially reduced by subjecting the fluid to increased pressure as by a piston or the like.

In my copending application, Serial No. 358,601, filed Feb. 14, 1920, are disclosed certain improved types of circuit interrupter of the general character aforesaid wherein in the foregoing and other difficulties are avoided by locating the fluid contacting medium preferably in an evacuated space, whereby obviously no gaseous medium is so entrapped and the present invention has among its objects that of providing a circuit interrupter of the same general type but wherein the aforementioned difficulties are obviated without requiring evacuation of the region about the contacting medium.

A further object is that of providing an exceedingly simple, rugged and reliable structure for the foregoing purposes which may be adapted to control currents of practically any desired magnitude.

Another object is that of providing such a circuit interrupter adapted to control either alternating or direct currents of relatively high magnitude without material arcing.

Other objects and advantages will herein-after appear.

In the accompanying drawing wherein are illustrated certain of the embodiments which the invention may assume in practice,

Fig. 1 is a longitudinal sectional view thereof, certain typical circuit connections therefor being illustrated diagrammatically; while,

Figs. 2 and 3 are similar views illustrating slightly modified forms of circuit interrupter.

In the construction illustrated in Fig. 1, a constricted tube 5 of glass or other insulating material is provided terminally with solid electrodes 6 and 7 of any preferred type normally electrically connected by a quantity 8 of a liquid conductive medium such for example as mercury. A conventional form of heating element which may comprise a resistive coil 9 is arranged about or adjacent to an intermediate portion of said tube as illustrated, whereby upon heating of such element as by a passage therethrough of current above a predetermined value, the mercury within the adjacent portion of the tube is adapted to become suddenly vaporized. Thereupon the liquid mercury above such vaporized portion thereof is suddenly expelled upwardly thereby interrupting electrical continuity of the column of mercury and interrupting circuit between the solid electrodes.

The tube 5 is preferably arranged in a vertical position as shown whereby following escape or condensation of the vaporized mercury the displaced body of liquid mercury is adapted to flow back within the tube thereby automatically re-establishing the interrupted circuit.

More specifically the electrode 7 is preferably secured within the lower end of the tube 5 by means of a liquid tight seal, whereas a conductive cap 10 is preferably cemented or otherwise secured to and outwardly of the lower portion of the tube as shown to provide a terminal for said electrode. The upper end of said tube is preferably flared somewhat, as illustrated, whereas a relatively enlarged cap 11 which may be of conductive material is similarly cemented to and about said flared upper end of said tube to make therewith also a liquid tight joint. The space within said cap above said tube is preferably of such capacity as to contain the entire body of mercury normally located within said tube.

The upper electrode 6 is permanently and electrically connected to the cap 11 by welding, soldering or in any other desired or

preferred manner. Also if desired, a further cap member 12 composed of brass or the like may be spun about the upper portion of the inner cap as illustrated to provide a good 5 electrical contacting surface for terminal connection of the electrode 6.

The inner diameter of the tube 5 is relatively large throughout the major portion of its length, the enclosed column of mercury being correspondingly thick and hence adapted to maintain electrical continuity irrespective of trapping of gas bubbles therein. However, said column is materially constricted as by collapsing the walls of the 10 tube at an intermediate point substantially as illustrated at 13, thereby restricting free circulation of the partially heated mercury between the regions adjacent the heater 9 and the free upper surface of the mercury 15 consequently reducing heat losses due to convection, and also preventing free boiling of the heated mercury. That portion of the mercury column which is subjected to direct action of the heater 9 is furthermore 20 maintained under a very considerable hydrostatic head due to the weight of the column of mercury thereabove plus the atmospheric pressure acting upon the top of said column. Thus a material degree of 25 superheating of the mercury is required to effect vaporization thereof, whereas when vaporization once occurs said hydrostatic head is very rapidly reduced due to expulsion of mercury from the tube and into the 30 enlarged cavity within the cap 11. Thus in turn the pressure upon the vaporized mercury is materially reduced with consequent increase in rate of expansion of the vapor whereby as a final result that portion of the 35 mercury column adjacent the heater is blown upwardly out of the tube or at least above the constriction thereof, thus effecting a sudden and wide separation of adjacent conductive surfaces for interruption of circuit 40 therebetween and extinguishment of any arc drawn incident to such circuit interruption.

Following condensation of the vaporized mercury or escape thereof from the interior of the tube the liquid mercury suspended 45 within the cap 11 is adapted to flow back under the force of gravity and reunite with the unexpelled portion of mercury located below the heater thereby re-establishing electrical continuity of the interrupter and if 50 during such reflux of liquid mercury an air bubble should be entrapped within the tube, the constriction of the passage within said tube inherently prevents passage of any bubble of such size as to impair conductivity 55 of the column, therebelow or beyond, whereas the electrode 6 is extended through and beyond said constriction for electrical contact with the mercury therebelow, whereby 60 the positiveness of the resetting action aforementioned is in no wise affected by the pres-

ence of any bubble which may be entrapped. Said constriction also serves to retard reflux of the liquid mercury, thereby delaying the aforescribed resetting action to afford a time element within which the switch controlled by the cutout device is adapted to 70 function.

With the circuit connections illustrated the heating coil 9 is connected in series with the load device 14 to be protected, a suitable electro-responsive switch 15 being arranged to control continuity of such joint circuit whereas the aforescribed interrupter is arranged to control energization of the closing coil of said switch whereby 75 obviously upon rise, above a pre-determined value, of the current taken by the load device in the circuit interrupter is adapted to act in the manner aforescribed to effect opening of the switch 15 and de-energization of such 80 joint circuit. The interrupter is thereafter adapted to reset automatically whereupon the main switch may be reclosed by momentary actuation of the push button 16.

The aforescribed circuit interrupter is 85 adapted to control alternating currents of relatively high magnitude and also to control direct currents of considerably less magnitude whereas where direct currents of greater magnitude are to be controlled the 90 form of the invention illustrated in Figs. 2 and 3 is preferable.

In Fig. 2 the general construction and arrangement is similar to that aforescribed, the tube 5^a being un-constricted internally. 100 The passage within said tube is, however, constricted as in the preceding construction. Thus an enlarged electrode 6^a of iron or other suitable conductive material is mechanically and electrically connected with 105 the cap 11 by means of a wire 17 or the like, said electrode being in general cylindrical in form and of a size to fill the tube 5^a. Said electrode, however, is flattened upon one side as indicated at 18, thus affording the 110 aforescribed constricted passage connecting the portions of the interior of the tube located respectively above and below said electrode.

A corresponding electrode 7^a also composed of iron or the like and of cylindrical shape and of a diameter such as to fill the interior of the tube is located at the bottom of said tube as illustrated and is electrically connected with the lower terminal cap thereof. Said electrode is in practice of such length that the upper end thereof is located adjacent the middle of the heating element 9 and materially spaced from the adjacent 115 terminal portion of the electrode 6^a, the intervening space being normally filled with mercury which also extends through the constricted passage aforementioned and within the upper portion of the tube in proximity to the cap 11.

The operation of this form of the device is precisely similar to that aforescribed, whereas the special construction and arrangement of electrodes adapts the same to

5 the control of direct currents of relatively high magnitude without material arcing.

Such capability of the device is dependent upon the fact that except under relatively high potentials an arc cannot be maintained 10 between a solid cathode and a mercury or other fluid anode. Thus upon sudden expulsion of the mercury between electrodes 7^a and 6^a, such as occurs upon normal functioning of the device, the circuit between 15 said electrodes is suddenly interrupted without arcing and irrespective of polarity since both of the contiguous electrodes are solid.

The upper end of the electrode 7^a is preferably rounded or convexed, as shown, to promote complete expulsion of the liquid mercury located thereabove, since any portion which is not at once expelled is caused to travel outwardly of the tube and nearer 25 to the heater and hence becomes vaporized immediately.

The construction illustrated in Fig. 3 is in all material respects similar to that of Fig. 2 except for the construction of the electrode 6^b which as illustrated is in the form 30 of an axially elongated annulus of exterior diameter sufficient to fill the interior of the tube completely, the opening 19 in said annulus constituting the aforescribed constricted passage for the mercury column.

The two latter described figures obviously possess all the aforescribed advantages of Fig. 1 in that the upper electrode extends below the constriction in the mercury column 40 and thus insures re-establishment of electrical continuity through the interrupter irrespective of possible trapping of air bubbles of appreciable magnitude above the constriction, whereas any relatively small bubbles which might be carried beyond the constriction will in any of the aforementioned instances be expelled upon heating of the column before the temperature of response of the device is attained.

50 Also in each of the constructions aforescribed the interruption of circuit occurs in an atmosphere of mercury vapor only, no atmospheric oxygen or other deleterious gaseous agency being present, whereby deterioration of the mercury due to contamination by the presence of such agents during arcing is entirely prevented.

It is of course to be understood that the constructions illustrated in Figs. 2 and 3 60 are adapted to control alternating as well as direct currents. Also it should be noted that the space within the cap 11 while preferably sealed against the escape of liquid mercury therefrom is nevertheless preferable in such communication with the outer

air as to render the pressure within said space and upon the column of mercury within the tube at all times substantially atmospheric pressure.

What I claim as new and desire to secure 70 by Letters Patent is:

1. A thermally controlled circuit interrupter comprising a container having a depending tubular extension to contain a column of conductive fluid which is liquid 75 at working temperatures, electrodes to be connected by said fluid, means restricting the cross sectional area of said column beyond the portions of said electrodes to be so connected and thermal means for subjecting said column of fluid to fluid pressure of its own vapor to force fluid from between said electrodes and past the constriction of said column for interrupting circuit between fluid surfaces intermediate said 85 electrodes.

2. A thermally controlled circuit interrupter comprising a container having a depending tubular extension to contain a column of conductive liquid, electrodes to be connected by said liquid and means exterior to said container to subject said column of liquid to fluid pressure of its own vapor for interrupting such connection between liquid surfaces, said column having 90 means associated therewith beyond the region of such circuit interruption to prevent free boiling of the liquid under the action of said thermic means to thereby provide for effecting such interruption suddenly. 95

3. A thermally controlled circuit interrupter comprising a substantially vertical column of conductive liquid, a support therefor having a reservoir located above said column and in communication therewith, 105 said column having associated means effecting constriction thereof adjacent said reservoir, electrodes having parts to be connected by an unconstricted portion of said column and thermic means to act upon such portion 110 of the column for subjecting the latter to fluid pressure of its own vapor, said constriction serving to prevent free circulation or boiling of the liquid under the action of said thermic means to thereby provide for 115 sudden ejection of a portion of said column from between said electrodes and within said reservoir for interruption of circuit between said electrodes.

4. A thermally controlled circuit interrupter comprising a substantially vertical column of conductive liquid of relatively 120 large cross sectional area having therein a constriction, electrodes to be connected by said liquid upon one side of said constriction, a support for said column having a relatively enlarged reservoir located upon the opposite side of said constriction and above said column in open communication therewith and thermic means for effecting va- 125

- porization of such liquid adjacent said electrodes for forcing the liquid above the region of vaporization upwardly beyond said constriction and within said reservoir, the 5 cross sectional area of said column being sufficient to permit automatic reflux of said liquid following escape or condensation of the vaporized liquid, subject to delay by said constriction.
- 10 5. A thermally controlled circuit interrupter comprising a substantially vertical column of conductive liquid of relatively large cross sectional area having therein a constriction, electrodes to be connected by 15 said liquid upon one side of said constriction, a support for said column having a relatively enlarged reservoir located upon the opposite side of said constriction and above said column in open communication therewith and thermic means for effecting vaporization of such liquid adjacent said electrodes for forcing the liquid above the region of vaporization upwardly beyond said constriction and within said reservoir, the 20 25 cross sectional area of said column being sufficient to permit automatic reflux of said liquid following escape or condensation of the vaporized liquid, subject to delay by said constriction, said constriction serving to prevent entrapment between said electrodes of any gas bubbles of size sufficient to prevent re-establishment of electrical connection therebetween.
6. A thermally controlled circuit interrupter comprising an elongated tube of insulating material to contain a column of mercury, means restricting the cross sectional area of said column, electrodes to be connected by said column and provided with 30 terminals located exteriorly of said tube, certain of said electrodes being arranged to shunt said restricted area of said column and thermic means associated with said column to effect sudden vaporization of a portion thereof adjacent said electrodes for up- 35 40 45
- ward expulsion of the mercury located therebetween to thereby provide for sudden interruption of circuit through said electrodes.
7. A thermally controlled circuit interrupter comprising an elongated tube of insulating material to contain a column of conductive liquid, means associated with said tube to provide a reservoir thereabove and in open communication therewith, means restricting the cross sectional area of said 50 55 column at a region adjacent said reservoir, electrodes to be connected by said liquid and provided with terminals located exteriorly of said tube, certain of said electrodes being arranged to shunt said restricted area of 60 said column and thermic means associated with said column to effect sudden vaporization of a portion thereof located between said electrodes for expulsion of liquid located therebetween upwardly and within 65 said reservoir to thereby provide for sudden interruption of circuit between said electrodes.
8. A thermally controlled circuit interrupter comprising an elongated tube of insulating material to contain a column of conductive liquid, means associated with said tube to provide a reservoir thereabove and in open communication therewith, means restricting the cross sectional area of said 70 75 column at a region adjacent said reservoir, electrodes to be connected by said liquid and provided with terminals located exteriorly of said tube, certain of said electrodes being arranged to penetrate said restricted area 80 of said column and thermic means associated with said column to provide for sudden vaporization of liquid between said electrodes for effecting expulsion of all the liquid between said electrodes to thereby interrupt 85 circuit substantially without arcing.

In witness whereof, I have hereunto subscribed my name.

ERWIN R. STOEKLE.
